UNITED STATES PATENT OFFICE.

ALBERT A. LEDERER, OF BUFFALO, NEW YORK.

MICROMETER-PROTRACTOR.

1,147,105.

Specification of Letters Patent. Patented July 20, 1915.

Application filed March 26, 1915. Serial No. 17,168.

To all whom it may concern:

Be it known that I, ALBERT A. LEDERER, a citizen of the United States, residing at Buffalo, in the county of Erie and State of New York, have invented certain new and useful Improvements in Micrometer-Protractors, of which the following is a specification.

My invention relates to micrometer protractors and particularly to means connected therewith for finely adjusting the same when measuring or setting angles closely.

One of the objects of my invention is to provide a micrometer protractor having means which render the same particularly useful in measuring or setting angles very closely and to have such means adaptable, as a modification of my invention, to a standard instrument, to adapt the same for a finer angular adjustment, than that for which it was originally made, without materially changing the construction of such an instrument, while incorporating the said means thereon.

Another object is to so construct the said means, as an attachment, that a horizontal clamping action can be made, upon which to base an angular adjustment, and thereafter execute a transverse clamping action, to bind said parts tightly together vertically, without interfering with the said horizontal clamping action and the adjustment connected therewith.

A further object of this invention is to provide an attachment, which can be easily read for very small changes in angular adjustment, and which will be simple in construction, and one which can be cheaply, but substantially made, so that it will be possible to sell the same at a popular price, either as a complete instrument or to provide the said means as an attachment to another instrument.

The standard protractor comprises a straight bar, integral with a graduated circular plate, from the center of which, projects a threaded post, which is also integral with the said circular plate. Concentric with the said post is a disk, having a zero mark and sometimes a vernier. Journalled on the said post, and fixed to the said disk, is a radial leaf, the outer end of which engages a transverse flat bar or straight edge. On the upper threaded end of the post, is a nut which clamps the parts together. Such an instrument can be adjusted by hand, for coarse readings of arc only. To render such an instrument adjustable and readable to the finer or closer changes in angular position, I have devised the means which are hereinafter described and illustrated in the drawings and what I claim is set forth.

In the drawings like figures refer to like parts.

Figure 1 is a top plan view of a standard protractor showing my attachment. Fig. 2 is a section taken on the line X—X of Fig. 1. Fig. 3 is a sectional elevation of the adjustable parts for making fine angular adjustment and readings. Fig. 4 is a perspective view of the horizontal clamp used and showing three pins in loose transverse engagement therewith. Fig. 5 is a perspective view of a triangular bracket. Fig. 6 is a perspective view of the pivoted and threaded bearing.

In Fig. 1, 1 is a graduated circular plate, extended to form the straight bar portion 2, and the arm 3. From the center of the plate 1, projects the post 4, upon which is journaled a disk 5. Also journalled on the said post 4, and fixed to the disk 5, by the screw 6, is the radial leaf 7, which engages the straight edge bar 8, and is clamped thereto by means of the thumb screw 9. In threaded engagement with the post 4, is the sleeve 10, the lower outer surface of which is smooth for engagement with the clamp 11, and the upper outer surface of which is threaded for engagement with the nut 12. The clamp 11 has jaws 13, which may be drawn together by the screw 14. Extending from the clamp 11, is an arm 15, to the outer end of which, is pivoted a bearing 16. Fixed to the disk 5, by screws, is the bracket 17, upon which is pivoted a threaded bearing 18. A rod 19, in threaded engagement with the bearing 18, is journalled with the bearing 16, and has a collar 19^b which shoulders on the bearing 16. The bearing 16 is extended to form a conical part 20, having a zero mark. A graduated and knurled cylinder 21 engages the rod 19 and butts up against the part 20. The rod 19 terminates in one end in a knurled knob 22 and upon the opposite end of the rod 19 is a knurled nut 23. Passing loosely through holes in the clamp 11, are three pins 24. These pins are a little longer than the thickness of the clamp 11. In contact with the upper end of these pins,

is a thin washer 25, over which is the nut 12. While in contact, the lower ends of said pins 24 is a washer 25^a.

In Fig. 2 is shown in section, the circular plate 1, the post 4, projecting above the plate 1, the sleeve 10 in threaded engagement with the post 4, the clamp 11 engaging the sleeve 10, and the pins 24, passing through the clamp 11, engaging the sleeve 10, and the pins 24, passing through the clamp 11, having their upper ends in contact with the washer 25 and the lower ends in contact with the washer 25^a.

In Fig. 3, is shown the rod 19, in threaded engagement with the bearing 18, which is pivoted to the triangular bracket 17. The rod 19 is shown journaled in the bearing 16, and adapted to revolve within an annular recess of the conical extension 20, is the collar 19^a, integral with the rod 19. The bearing 16 is pivoted to the arm 15 (of the clamp 11) by the screw 15^a. The graduated cylinder 21 is journaled on the rod 19 and its outer flat surface is recessed to receive the shank 25 of the nut 23, in threaded engagement with the rod 19.

In Fig. 4, the pins 24 are shown partially entering holes in the clamp 11. These pins 24, when in use in the assembled device extend only a short distance beyond the upper and lower faces of the clamp 11.

In Fig. 5, the triangular bracket 17, is shown to be thinner toward its small end, so as to be adapted to lie over the leaf 7, while being screwed to the disk 5. (See Fig. 1.) In the small end of the bracket 17 is the hole 17^a.

In Fig. 6 is shown the threaded bearing 18 with its lower pivot end 18^a, adapted to engage the hole 17^a in the bracket 17 (see Fig. 5).

When using the form of my invention shown in the figures, referring particularly to Fig. 1, the operator begins to set the parts to Fig. 1, the operator begins to set the parts 2 and 8, approximately to the angle desired, or that to be measured, having first loosened the nut 12. After roughly setting the instrument to the angle desired, he turns the screw 14 to tighten the clamp 11, upon the sleeve 10, which has previously been made tight upon the post 4. He is now ready for the fine adjustment and this he can get by turning the threaded rod 19 for a reading upon the vernier 5^a or on the graduated cylinder 21. There is a relation between the pitch of thread on the rod 19, the radial distance of the axis of the rod 19 from the center of the post 4, the diameter of the cylinder 21 and the spacing of the calibrated circumferential marks upon the cylinder 21, to denote small increments of angle in adjustment. This relation is predetermined before making up the instrument, so as to read to as fine an increment of angle as desired. After making the nut

23 loose, the cylinder 21 can be turned with reference to the zero mark on the cone 20, and afterward clamped against the collar 19^a by tightening the nut 23, so that the cylinder 21 will turn with the rod 19.

After the operator has adjusted the instrument to the desired angle, he next tightens the nut 12 (see Fig. 2) to cause the pins 24 to force the washer 25^a to press the leaf 7, and disk 5, hard against the plate 1, binding thees parts together and setting them to retain the angular position of the parts 2 and 8, after adjustment. The use of the pins 24 does not in any way disturb the hold of the clamp 11 upon the sleeve 10, which acts as part of the post 4.

As the details of my invention may be varied without departing from the spirit of the same, I do not wish to be confined to the details herein illustrated and described.

Hence I claim:

1. In a micrometer protractor, the combination of a graduated circular plate having a straight edged extension and a central member integral with said plate, a disk 90 on said plate adapted to turn concentric to said member, a leaf extending from said disk to which it is fixed, a straight edged piece slidably engaging said leaf transverse to the same and adapted to be clamped thereto, a bracket fixed to said disk, a threaded bearing pivoted to said bracket, clamping means engaging said central member, a journal bearing pivoted to said clamping means, a rod in threaded engagement with said threaded bearing and journaled with said journal bearing, and means holding said rod from longitudinal movement in said journal bearing.

2. In a micrometer protractor, the combination of a graduated circular plate having a straight edged extension and a central member integral with said plate, a disk on said member adapted to turn concentric to said post, a leaf extending from said disk to which it is fixed, a straight edged piece slidably engaging said leaf transverse to the same and adapted to be clamped thereto, a bracket fixed to said disk, a threaded bearing pivoted to said bracket, clamping means engaging said central member, a journal bearing pivoted to said clamping means, a rod in threaded engagement with said threaded bearing and journaled with said journal bearing, means holding said rod from longitudinal movement in said journal bearing, and a graduated cylinder concentric with and adapted to be clamped on said rod.

3. In a micrometer protractor, the combination of a graduated circular plate having a straight edged extension and a central post integral with said plate, a disk on said plate adapted to turn concentric to said member, a leaf extending from said disk to

which it is fixed, a straight edged piece slidably engaging said leaf transverse to the same and adapted to be clamped thereto, a bracket fixed to said disk, a threaded bearing pivoted to said bracket, clamping means

engaging said central member, a journal bearing pivoted to said clamping means, a rod in threaded engagement with said threaded bearing and journaled with said journal bearing, means holding said rod from longitudinal movement in said journal bearing, a graduated cylinder concentric with and adapted to be clamped on said rod, and other clamping means adapted to bind

70

5 10 journal bearing, means holding said rod from longitudinal movement in said journal bearing, a graduated cylinder concentric with and adapted to be clamped on said rod, and other clamping means adapted to bind

75

15 the disk and said plate vertically, said other clamping means being independent of said first mentioned clamping means in its action.

4. In a micrometer protractor, the combination of a graduated circular plate having

20 a straight edged extension and a central post integral with said plate, a sleeve engaging said post, a disk on said plate adapted to turn concentric to said post, a leaf extending from said disk to which it is fixed, a straight

80

25 edged piece slidably engaging said leaf transverse to the same and adapted to be clamped thereto, a bracket fixed to said disk, a threaded bearing pivoted to said bracket, clamping means engaging said sleeve on said

85

30 post, a journal bearing pivoted to said clamping means, a rod in threaded engagement with said threaded bearing and journaled with said journal bearing, and means holding said rod from longitudinal move-

90

35 ment in said journal bearing.

95

5. In a micrometer protractor, the combination of a graduated circular plate having a straight edged extension and a central post integral with said plate, a sleeve engaging

100

40 said post, a disk on said plate adapted to turn concentric to said post, a leaf extending from said disk to which it is fixed, a straight edged piece slidably engaging said leaf transverse to the same and adapted to be

105

45 clamped thereto, a bracket fixed to said disk, a threaded bearing pivoted to said bracket, clamping means engaging said sleeve on said post, a journal bearing pivoted to said clamping means, a rod in threaded engagement with said threaded bearing and journaled with said journal bearing, means holding

110

50 said rod from longitudinal movement in said journal bearing, and a graduated cylinder concentric with and adapted to be clamped on said rod.

115

55 6. In a micrometer protractor, the combination of a graduated circular plate having a straight edged extension and a central post integral with said plate, a sleeve engaging

120

60 said post, a disk on said plate adapted to turn concentric to said post, a leaf extending from said disk to which it is fixed, a straight edged piece slidably engaging said leaf transverse to the same and adapted to be

125

65 clamped thereto, a bracket fixed to said

disk, a threaded bearing pivoted to said bracket, clamping means engaging said sleeve a journal bearing pivoted to said clamping means, a rod in threaded engagement with said threaded bearing and journaled with said journal bearing, means holding said rod from longitudinal movement in said journal bearing, a graduated cylinder concentric with and adapted to be clamped on said rod, and other clamping means adapted to bind

75

7. In a micrometer protractor, the combination of a graduated circular plate having a straight edged extension and a central post integral with said plate, a sleeve engaging said post, a disk on said plate adapted to turn concentric to said post, a leaf extending from said disk to which it is fixed, a straight edged piece slidably engaging said leaf transverse to the same and adapted to be clamped thereto, a bracket fixed to said disk, a threaded bearing pivoted to said bracket, clamping means engaging said sleeve on said post, a journal bearing pivoted to said clamping means a rod in threaded engagement with said threaded bearing and journaled with said journal bearing, means holding said rod from longitudinal movement in said journal bearing, and pins passing through transverse holes in said clamping means near said sleeve, said pins being each longer than the thickness of the part of said clamping means surrounding said sleeve, a nut in threaded engagement with said sleeve, said pins being positioned to transmit a binding action from said nut to said disk to force the same vertically against said plate.

100

8. In a micrometer protractor, the combination of a graduated circular plate having a straight edged extension and a central post integral with said plate, a sleeve engaging said post, a disk on said plate adapted to turn concentric to said post, a leaf extending from said disk to which it is fixed, a straight edged piece slidably engaging said leaf transverse to the same and adapted to be clamped thereto, a bracket fixed to said disk, a threaded bearing pivoted to said bracket, clamping means engaging said sleeve on said post, a journal bearing pivoted to said clamping means, a rod in threaded engagement with said threaded bearing and journaled with said journal bearing, means holding said rod from longitudinal movement in said journal bearing, a graduated cylinder concentric with and adapted to be clamped on said rod, and pins passing through transverse holes in said clamping means near said sleeve, said pins being each longer than the thickness of the part of said clamping means surrounding

115

120

125

130

said sleeve, a nut in threaded engagement with said sleeve, said pins being positioned to transmit a binding action from said nut to said disk to force the same vertically against said plate.

9. In a micrometer protractor, the combination of a graduated circular plate having a straight edged extension and a central post integral with said plate, a sleeve engaging 10 said post, a disk on said plate adapted to turn concentric to said post, a leaf extending from said disk to which it is fixed, a straight edged piece slidably engaging said leaf transverse to the same and adapted to 15 be clamped thereto, a bracket fixed to said disk, a threaded bearing pivoted to said bracket, clamping means engaging said sleeve a journal bearing pivoted to said 20 sleeve a journal bearing pivoted to said clamping means, a rod in threaded engagement with said threaded bearing and journaled with said journal bearing, means

holding said rod from longitudinal movement in said journal bearing, a graduated cylinder concentric with and adapted to be clamped on said rod, and other clamping 25 means adapted to bind the disk and said plate vertically, said other clamping means being independent of said first mentioned clamping means in its action, and pins passing through transverse holes in said clamping means near said sleeve, said pins being each longer than the thickness of the part of 30 said clamping means surrounding said sleeve, a nut in threaded engagement with said sleeve, said pins being positioned to 35 transmit a binding action from said nut to said disk to force the same vertically against said plate.

ALBERT A. LEDERER.
